UNITED STATES PATENT OFFICE.

PIUS J. DURBIN, OF LOS ANGELES, CALIFORNIA, ASSIGNOR OF ONE-HALF TO FINGAL C. ORR.

SWINGING CLOSURE.

Application filed July 3, 1924. Serial No. 723,936.

To all whom it may concern:

Be it known that I, PIUS J. DURBIN, a citizen of the United States, residing at Los Angeles, in the county of Los Angeles and 5 State of California, have invented certain new and useful Improvements in Swinging Closures, of which the following is a specification.

My invention relates to improvements in 10 hinged or swinging closures such as gates, doors and the like, and has for its principal objects the provision of a swinging closure that is relatively simple in structure, capable of being easily and cheaply produced and 15 installed; to provide a swinging closure that may be readily manipulated and easily shifted from one position to another and further, to provide the swinging closure with simple and efficient means whereby it may 20 be firmly held while closed or while in full open, or in partially opened positions.

With the foregoing and other objects in view, my invention consists in certain novel features of construction and arrangement of 25 parts that will be hereinafter more fully described and claimed and illustrated in the accompanying drawings in which:

Fig. 1 is an elevational view of a swinging closure embodying the principles of my 30 invention and of the type that is particularly adapted for use as a farm gate.

Fig. 2 is a plan view of the swinging closure with dotted lines showing same in full open position.

Fig. 3 is a detail view partly in section, and showing the form of latch bar that is 35 used for securing the closure in partially opened positions.

Fig. 4 is a detail section of a latch bar 40 lifting device that may be employed in carrying out my invention.

Fig. 5 is a sectional view of a closure constructed in accordance with my invention and which swings on a horizontal axis.

Referring by numerals to the accompanying drawings and particularly to the form 45 of closure illustrated in Figs. 1 and 2, 10 designates a gate that is connected at one end, by suitable hinges 11 to a post or upright 12 and the free end of said gate when closed, occupies a position immediately adjacent to a post or upright 13.

Projecting outwardly from post 12 and 50 on the opposite side from hinges 11 is a bracket 14 on the outer end of which is a

vertically disposed pintle 15. Pivotedly mounted on this pintle is one of a latching bar 16 that extends lengthwise of the closure 10 and at the free end of the latter, said bar passes through a vertically disposed keeper 17 that is secured to the gate or closure. 60

The end of latch bar 15 projects a short distance beyond the keeper 17 so as to overlie the corresponding side of post 13 and projecting from the latter is an upstanding hook 18 that is adapted to receive and hold the end of the latch bar when the closure or gate is closed. 65

As a further means of securing the closure in closed position, bar 16 is provided on its lower edge near its free end with a notch 19, that engages the lower portion of loop 17 when the closure is in closed position. 70

Additional notches such as 19^a may be 75 formed in the lower edge of bar 16 at suitable distances apart for engaging the lower portion of keeper 17 to hold the closure in full open or partially opened positions.

Secured to bar 16 near the end that is 80 pivotally connected to pintle 15 is one end of a retractile spring 20 and the opposite end thereof being secured to gate or closure 10. When the gate or closure is closed, this spring is extended and under tension, with the result, that when the end of latch bar 16 is lifted from hook 18, the retractile effort of the extended spring will be exerted to 85 swing the gate or closure into full or partially open position.

During this opening movement of the gate or closure, the free end of bar 16 slides through loop 17 and if it is desired to lock 90 said gate or closure in its full or partially opened position, the bar is lowered in the slot in keeper 17 until one of the notches 19^a 95 engages the lower portion of said keeper.

In order to facilitate the lifting of latch bar 16, a short rod such as 21 may be journaled in the bar plate of keeper 17, and 100 which rod is provided with an operating handle 22 and with an eccentric 23 that is positioned directly beneath said latch bar (see Fig. 4).

In Fig. 5 I have shown a window hinged 105 at its upper edge so as to swing on a horizontal axis and said window having associated therewith a latch bar of my improved construction.

In this construction the upper end of the 110 latch bar 24 is pivotally connected to a

bracket 25 at a point above and in front of the hinge of the window and formed in the lower portion of said latch bar is a notch 26 that receives the keeper 27 when the window or closure is swung upward into open position as shown by dotted lines in Fig. 5.

The principles of my invention may be embodied in various forms of closures, for instance, gates, doors, windows, shutters,

10 ventilating panels, in fact any hinged or swinging closure, wherein a simple, inexpensive, strong, durable and efficient operating and latching means is desired or may be advantageously used.

15 It will be understood that minor changes in the size, form and construction of the various parts of my improved swinging closure may be made and substituted for those herein shown and described without departing from the spirit of the invention, the scope of which is set forth in the appended claims.

I claim as my invention:

1. The combination with a hinged closure, 25 of a latching bar pivotally connected at one end to a fixed member that is spaced apart from the hinge of said closure, a keeper carried by the closure and through which the opposite end portion of said latching bar is adapted to slide and a retractile spring 30 connected to and arranged between said closure and latching bar.

2. The combination with a hinged closure, 35 of a latching bar pivotally connected at one end to a fixed member that is spaced apart from the hinge of said closure, a keeper car-

ried by the closure and through which the opposite end portion of said latching bar is adapted to slide, the lower edge of said latching bar being provided with notches that are adapted to receive the lower portion of said keeper to hold said closure in closed, full, open or partially opened positions and a retractile spring secured to and arranged between said closure and latching bar. 40

3. The combination with a hinged closure, of a latching bar pivotally connected at one end to a fixed member at a point spaced apart from the hinge for said closure, a latching bar keeper carried by the end of the closure opposite from its hinged end, said latching bar being arranged to slide freely through said keeper and a fixed hook that is adapted to receive the free end of the latching bar when the closure is in closed 50 position.

4. The combination with a hinged closure, of a latching bar pivotally connected at one end to a fixed member at a point spaced apart from the hinge for said closure, a 60 latching bar keeper carried by the end of the closure opposite from its hinged end, said latching bar being arranged to slide freely through said keeper, a fixed hook that is adapted to receive the free end of the latching bar when the closure is in closed position and a retractile spring secured to and arranged between said closure and latching bar. 65

In testimony whereof I affix my signature. 70

PIUS J. DURBIN.
